(57) **CLAIM**

The ornamental design for a breast pump, as shown and described.

DESCRIPTION

FIG. 1 is a front, bottom, and left perspective view of a first embodiment of a breast pump of the present invention;

FIG. 2 is a front, top, and right perspective view of the invention illustrated in FIG. 1;

FIG. 3 is a front view of the invention illustrated in FIG. 1; FIG. 4 is a left side view of the invention illustrated in FIG. 1, a right side view being the mirror image thereof;

FIG. 5 is a rear view of the invention illustrated in FIG. 1; FIG. 6 is a top view of the invention illustrated in FIG. 1; FIG. 7 is a bottom view of the invention illustrated in FIG. 1;

FIG. 8 is a front, top, and left perspective view of a second embodiment of a breast pump of the present invention;

FIG. 9 is a top view of the invention illustrated in FIG. 8; FIG. 10 is a front view of the invention illustrated in FIG. 8;

FIG. 11 is a left side view of the invention illustrated in FIG. 8, a right side view being the mirror image thereof; FIG. 12 is a bottom view of the invention illustrated in FIG. 8;

FIG. 13 is a rear view of the invention illustrated in FIG. 8; FIG. 14 is a front, top, and left perspective view of a third embodiment of a breast pump of the present invention;

FIG. 15 is a top view of the invention illustrated in FIG. 14; FIG. 16 is a front view of the invention illustrated in FIG. 14; FIG. 17 is a left side view of the invention illustrated in FIG. 14, a right side view being the mirror image thereof;

(Continued)

FIG. 18 is a bottom view of the invention illustrated in FIG. 14;

FIG. 19 is a rear view of the invention illustrated in FIG. 14; FIG. 20 is a front, top, and left perspective view of a fourth embodiment of a breast pump of the present invention; FIG. 21 is a top view of the invention illustrated in FIG. 20; FIG. 22 is a front view of the invention illustrated in FIG. 20; FIG. 23 is a left side view of the invention illustrated in FIG. 20, a right side view being the mirror image thereof; FIG. 24 is a bottom view of the invention illustrated in FIG. 20;

FIG. 25 is a rear view of the invention illustrated in FIG. 20; FIG. 26 is a front, top, and left perspective view of a fifth embodiment of a breast pump of the present invention; FIG. 27 is a front, top, and left perspective view of the invention of FIG. 26, with a disclaimed portion thereof rotated to a second position;

FIG. 28 is a front view of the invention illustrated in FIG. 26; FIG. 29 is a left side view of the invention illustrated in FIG. 26, a right side view being the mirror image thereof; FIG. 30 is a top view of the invention illustrated in FIG. 26; FIG. 31 is a rear view of the invention illustrated in FIG. 26; and,

FIG. 32 is a bottom view of the invention illustrated in FIG. 26.

The broken lines in the drawings illustrate portions of the breast pump that form no part of the claimed design.
